UNITED STATES PATENT OFFICE

2,398,651

ELECTRICAL RELAY

Anthony H. Lamb, Hillside, N. J., assignor to
 Weston Electrical Instrument Corporation,
 Newark, N. J., a corporation of New Jersey

Application November 27, 1942, Serial No. 467,158

3 Claims. (Cl. 200—110)

This invention relates to electrical relays and more particularly to electrical relays of the instrument type in which the moving system is supported by jewel bearings.

The circuit connection to the pointer or contact arm of an instrument type relay is through a spiral spring that extends between a metal abutment on the upper bridge of the instrument relay and a metal abutment that is anchored to the upper pivot of the moving coil. This spring is very thin in relays of high sensitivity and consequently can carry only a limited current. Excessive current oxidizes the spring and distorts the convolutions even though the current is not sufficient to burn or destroy the spring.

An object of the invention is to provide an instrument type relay that can control current flow of a magnitude substantially higher than that which may be carried by the spring connection to the relay contact. An object is to provide an instrument relay in which the moving system is pivotally supported by jewel bearings, and one of the "jewels" is metallic and establishes a circuit connection to the relay contact arm through the metal staff that is seated in the jewel. More specifically, an object is to provide an instrument relay in which the moving system includes a staff that is pivotally supported in a metal rhodium-plated bearing, the staff and bearing constituting a circuit connection to the relay contact arm.

These and other objects and advantages of the invention will be apparent from the following specification when taken with the accompanying drawing in which:

Fig. 1 is a fragmentary plan view of an instrument type relay embodying the invention; and

Fig. 2 is a fragmentary sectional view through the upper bearing of the moving coil, and with a diagram of a part of the relay circuit added to the view.

As shown in the drawing, the base 1 of the relay is of insulating material, preferably a molded plastic, with an integral abutment 2 having a groove 3 for receiving the heads of bolts 4 that secure the core 5 and the contact-supporting plate 6 to the inner face of the abutment. The coil 7 of the relay moving system is pivotally supported for angular movement in the gaps between the core 5 and the pole pieces 8 of the permanent magnet 9. The moving system includes the pivot post 10 that is cemented to the coil 7, the contact arm 11 and the inner spring abutment 12 that are clamped upon the pivot post by the nut 13, and the steel pivot 14 that is set into the end

of the pivot post. The outer end of the spiral spring 15 is secured to the outer abutment 16 that is supported upon the upper bridge 17 which, in turn, is mounted upon the base 1 by the studs 18.

10 The current supply to the contact arm 11 is through the spring 15 and its abutments, and the circuit connection to the outer abutment 16 may be through the mounting posts 18 and bridge 17, or directly to the projecting lug 18' of the abutment. The relatively fixed contacts 19 of the relay are carried by screws 20 that are threaded into bushings 21 mounted on the hooked arms 22 of the insulating plate 6. A spring washer 23 is arranged between a face of each supporting arm 22 and an associated bushing 21 to lock the contact screw against inadvertent rotation, and the washer has an extension 24 to which a circuit connection may be soldered.

20 The several parts that have been described may be of any desired design as their particular constructions and relationships are not important features of this invention. The drawing illustrates the relay that is described and claimed in 25 Patent No. 1,866,436, Edward F. Weston; and reference is made to that patent for a disclosure of appropriate constructions for the parts of the relay that are not illustrated in the drawing of this patent.

30 In accordance with this invention, at least the upper "jewel" bearing and, if desired, the lower jewel bearing for supporting the moving system are metallic and provide a current-conducting connection between the fixed parts of the relay 35 and the moving system. As shown in Fig. 2, the upper bearing is a screw 25, of brass or other metal of good electrical conductivity, that is threaded through the bridge 17 and locked in place by the nut 26 that also serves to secure the outer spring abutment 16 to the bridge. The concave inner end of the screw 25 has an attached layer 27 of rhodium that is preferably applied by an electroplating process.

45 The rhodium layer 27 is very hard and permanent, and the finish is very smooth when the rhodium is plated upon the accurately shaped and polished surface of the screw. The coefficient of friction with the conventional polished steel staff is of the order of that obtained with the sapphire 50 jewels, and the rhodium-surfaced jewel may be substituted for sapphire jewels in various types of instruments. The new jewel has special advantages in electrical relays as current may be conducted to the pointer or contact arm through the jewel screw.

The electrical circuits of the relay, as shown diagrammatically in Fig. 2, include a connection 30 from one terminal of a current source, such as a battery 31, to the outer spring abutment 16, and connections 32, 32' from the other terminal of the current source to the respective contacts 19, 19' through loads 33, 33'. According to prior practice, the only conductive path to the contact arm 11 was through the spring 15 that established a definite limit for the current that could be handled by the relay. The rhodium plated jewel screw 25, pivot 14 and pivot post 10 provide an additional current conductive path and the current flow through the relay contacts may therefore be increased. The resistance of the spring 15 may be of the order of up to one ohm, and the resistance of the conductive path through the jewel screw will be no higher. The total current flow to the contact arm 11 divides between the spring 15 and the conductive jewel bearing in a ratio inverse to their respective resistances, and the total current flow may be increased to a value considerably greater than that which may flow through the spring 15.

It is to be understood that the invention is not limited to the described embodiment, and that various changes may be made in the illustrated construction without departure from the spirit of my invention as set forth in the following claims.

I claim:

1. In an electrical relay of the instrument type, a moving system comprising a coil carrying a pointer for cooperation with a relatively station-

- ary contact, metal pivot staffs secured to said coil, a magnet having polar surfaces spaced apart by an air gap, bearings cooperating with said staffs to support said coil for angular movement in said gap, one of said staffs being electrically connected to said contact arm and the cooperating bearing being a rhodium plated metal bearing, and means for completing an electrical circuit to said contact arm in parallel with the connection provided by 5 said staff and cooperating rhodium-plated bearing; said means comprising a spiral spring, a fixed abutment in which said rhodium plated contact is mounted and to which the outer end of said spring is secured, and an abutment on said 10 moving system electrically connecting the inner end of said spring to said contact arm.
2. In an electrical relay, a moving system including a coil carrying a contact arm, a magnet having an interpolar gap, means comprising staffs on said moving system and bearings supporting said coil for angular movement in said gap and means including one of said bearings and its associated staff forming an electrical circuit connection to said contact arm, the said bearing being a metal screw having a surface of rhodium 15 engaged by the cooperating staff.
3. In an electrical relay, the invention as recited in claim 2, wherein said means includes a spiral spring constituting a current-conducting path in parallel with said rhodium-surfaced jewel and cooperating staff.

ANTHONY H. LAMB.
